Application filed April 18, 1900. Serial No. 13,394. Term of patent 14 years.

To all whom it may concern:

Be it known that I, JAMES T. PINNELL, a citizen of the United States, residing at Vienna, in the county of Maries and State of Missouri, have invented and produced a new and original Design for Pencils, of which the following is a specification.

My invention is a design for pencils.

The accompanying drawing illustrates a perspective view of the design.

The reference-numeral 1 designates the pencil, having at its upper end a tip consisting of two heads joined back to back and surmounted by a hat 2, having a brim 3.

The leading features of the design are the 15 heads or faces joined as shown and the hat above the same.

I claim—
